UNITED STATES PATENT OFFICE.

JOHN MASON, OF NEW YORK, N. Y.

DESIGN FOR A HANDLE FOR SPOONS, FORKS, &c.

SPECIFICATION forming part of Design No. 20,381, dated December 9, 1890.

Application filed November 6, 1890. Serial No. 370,547. Term of patent 7 years.

To all whom it may concern:

Be it known that I, JOHN MASON, a citizen of the United States, residing at New York, in the county and State of New York, have invented and produced a new and original Design for a Handle for Spoons, Forks, and other Articles, of which the following is a specification, reference being had to the accompanying drawing, forming a part thereof, which drawing represents a face view of my newly-designed handle applied to a spoon.

The leading features of my design consist in the panel A and adjoining oval field B, the former bearing in relief the ornamental scroll

C and having the ornamental borders D D in ¹⁵ relief, while the said field B bears in relief the ornamental scroll E and border F, as shown in the accompanying drawing.

I claim—

The design for a handle for spoons, forks, ²⁰ and other articles, substantially as shown and described.

Signed at the city of New York this 3d day of November, 1890.

JOHN MASON.
